UNITED STATES PATENT OFFICE.

ROBERT H. JACKSON, OF WILLINGTON, SOUTH CAROLINA.

SKIMMING EVAPORATOR.

Application filed April 20, 1925, Serial No. 24,654. Renewed April 12, 1926.

The invention contemplates the provision of an apparatus for skimming molasses by percolating the molasses through a perforated trough which separates the extraneous matter, and conveys the latter from the apparatus to a suitable receptacle arranged to receive the same, the trough being movable to ultimately convey the pure molasses into a compartment from which it can be drawn as desired.

The nature and advantages of the invention will be better understood when the following detailed description is read in connection with the accompanying drawings, 15 the invention residing in the construction, combination and arrangement of parts as claimed.

In the drawings forming part of this application, like numerals of reference indicate similar parts in the several views, and wherein:

Figure 1 is a side elevation of the apparatus.

Figure 2 is a top plan view showing by dotted lines the position of the perforated trough for depositing the pure molasses into a storage compartment.

Figure 3 is a sectional view taken on line 3—3 of Figure 2.

Figure 4 is a sectional view taken on line 4—4 of Figure 1.

The apparatus forming the subject matter of the present invention may be constructed from any suitable material and also vary in size and shape without departing from the spirit of the invention. The apparatus includes a tank 10 which is provided with a filling opening 11 which is normally closed by a stopper of any suitable design. Arranged on top of the tank 10 is a chamber or compartment 12 which communicates with the tank 10 through an opening 13. The communication however is controlled by a slide valve 14 which operates in suitable guides 15 and actuated by a float 16. The float is connected with the valve 14 by means of a suitable crank arm 17 journalled in a bracket 18 secured to the bottom of the compartment 12. Arranged alongside of the compartment 12 is an additional compartment or chamber 19 which is considerably larger than the compartment 12, and in which compartment 19 the molasses is conveyed after the extraneous matter has been completely separated therefrom. The chamber or compartment 19 is

provided with an outlet nipple 20 through which the molasses can be drawn from the compartment as desired, the nipple of course being adapted to be normally closed by a suitable stopper.

Rising from the tank 10 adjacent one end thereof is a pipe 21 which has its free end deposited immediately above a perforated trough 22. This trough is provided with a yoke 23 which is utilized to support the latter upon the pipe 21 as shown in Figure 3, while the trough adjacent the other end thereof is provided with a discharge nipple 24 which depends from the trough, as shown. Projecting from the opposite sides of this nipple 24 are hooks 25 which are adapted to repose upon the upper edges of the particular compartment over which the trough is arranged, to assist in supporting the trough in position for use. As shown in Figure 2 the trough may be arranged directly above the compartment 12, which position it occupies while the molasses is being percolated with a view of separating the extraneous matter therefrom, and subsequently shift it to the dotted line position shown in Figure 2, which it occupies when it is desired to convey the molasses to the storage compartment 19. The trough is

provided with a false perforated bottom 26, so that when the molasses is conveyed to the trough, it passes through the perforated bottom 26, and eventually finds its way through the nipple 24 into the compartment or chamber 12. The extraneous matter separated from the molasses passes over the perforated bottom 26, and subsequently passes from the trough through a spout 27, which projects laterally from the trough as shown in Figure 2. The extraneous matter is conveyed into a suitable receptacle not shown, but which is adapted to be arranged beneath the spout 27.

In practice, the tank 10 is filled with molasses through the opening 11, and the apparatus then is placed upon a suitable heater with a view of boiling the molasses. As the molasses boils, it passes upwardly through the pipe 21 to the perforated trough above described, wherein the extraneous matter is separated from the molasses as above described. The molasses passes through the perforated bottom 26 and is conveyed to the compartment or chamber 12. As this compartment fills up, the float 16 is raised, thereby opening the valve 14 to allow the molas-

ses to pass from the compartment 12 back into the tank 10. As long as the perforated trough remains positioned above the compartment or chamber 12, the molasses will 5 continue to pursue this course until it is completely free of the extraneous matter. Then the trough is shifted to the position shown by dotted lines in Figure 2, so that when the molasses is again conveyed to the 10 trough through the pipe 21, it will be deposited within the storage chamber or compartment 19, from which it can be drawn in any desired quantity through the outlet nipple 20.

15 While it is believed that from the foregoing description, the nature and advantages of the invention will be readily apparent, I desire to have it understood that I do not limit myself to what is herein shown and 20 described, and that such changes may be resorted to when desired as fall within the scope of what is claimed.

Having thus described the invention, I claim:

25 1. An apparatus of the character described comprising a liquid containing tank adapted to be subjected to heat, an overflow pipe rising from the tank, a trough arranged above the tank to receive the liquid from said 30 pipe and separate the extraneous matter from said liquid, a strainer arranged within said trough in spaced parallel relation to the bottom thereof, a compartment arranged above the tank to receive the liquid from 35 said trough, valve controlled communication between the compartment and tank whereby the liquid is returned to the tank, and a spout projecting from said trough and through which the extraneous matter 40 passes from the latter.

2. An apparatus of the character described comprising a liquid containing tank adapted to be subjected to heat, an overflow pipe ris-

ing from the tank, a trough arranged above the tank to receive the liquid from said pipe 45 and separate the extraneous matter from the liquid, a foraminated element arranged within the trough in spaced parallel relation to the bottom thereof, a spout leading from the trough through which the extraneous matter 50 passes from the latter, a compartment arranged above the tank and beneath said trough and communicating with the tank through an opening therein, said compartment being adapted to receive the liquid 55 from said trough, and a float actuated valve controlling the communication between the compartment and said tank.

3. An apparatus of the character described, comprising a liquid containing tank adapted 60 to be subjected to heat, independent compartments arranged above the tank side by side, one of said compartments communicating with said tank, a float actuated valve controlling said communication, an overflow 65 pipe rising from the tank, a trough supported by said pipe and capable of lateral movement, said trough being normally deposited above one of said compartments and adapted to receive the liquid from said pipe, and 70 separate the extraneous matter therefrom, a screen arranged within the trough in spaced parallel relation to the bottom thereof, said trough being designed to return the liquid to said tank through said compartment incident to the opening of said valve, a spout projecting from said trough and through which the extraneous matter passes 75 therefrom, and said trough being adapted to be arranged in communication with the other of said compartment to finally deposit the liquid in the latter for the purpose specified.

In testimony whereof I affix my signature.

ROBERT H. JACKSON.
